UNITED STATES PATENT OFFICE.

HUBERT L. SPENCE, OF CLEVELAND, OHIO, ASSIGNOR TO THE NATIONAL MALLEABLE CASTINGS COMPANY, OF CLEVELAND, OHIO, A CORPORATION OF OHIO.

YOKES FOR RAILWAY-CARS.

1,342,696.

Specification of Letters Patent.

Patented June 8, 1920.

Application filed August 22, 1917, Serial No. 187,510. Renewed December 11, 1919. Serial No. 344,269.

To all whom it may concern:

Be it known that I, HUBERT L. SPENCE, a citizen of the United States, residing at Cleveland, Cuyahoga county, Ohio, have invented new and useful Improvements in Yokes for Railway-Cars, of which the following is a specification, reference being had to the accompanying drawings, in which—

Figure 1 is an elevation of a yoke embodying my invention; and

Fig. 2 is a bottom plan thereof.

My invention relates to yokes for railway cars, and consists in providing a yoke with a removable lower arm, so that the coupler 15 may easily be assembled with the yoke, ready access may be had to the draft rigging, and the coupler and draft rigging may be removed separately, without disturbing the position of the upper arm or main portion 20 of the yoke on the car. My invention also consists in the construction and coöperation of the parts which I shall hereinafter describe and claim.

Referring to the drawings, the upper arm 25 2 of the yoke terminates at its rear end in a vertical downwardly extending portion 3, and at its forward end in the depending webs 4. The vertical rear portion 3 of the upper arm 2 has at its lower end a reduced 30 extension 5. The lower yoke arm 6 has, at its rear end, an aperture 7 extending vertically through it for reception of the extension 5, and both the extension 5 and the arm 6 have registering horizontal openings for 35 the pin 8 which supports the rear end of the lower arm when in assembled position. The opening in the extension 5 for the pin 8 is elongated in a horizontal direction so that the pin 8 is freed from any stresses other 40 than those due to the weight of the parts.

The forward end of the lower yoke arm is of T-shape, and the inner faces of the arms 9 of the T are adapted to enter horizontal slots 10 in the forward faces of the 45 webs.

After the coupler and draft rigging parts (not shown) have been placed in position in the upper yoke arm 2, the lower yoke arm 6 is applied by a rearward movement so as 50 to bring the arms 9 of the T into position in the slots 10, so that the forward end of the yoke arm 6 is not only supported in the slots 10, but its arms also engage the outer faces of the webs 4 and thereby prevent spreading. 55 Sufficient clearance is provided at α in the

slots 10 so that when the forward end of the lower yoke arm 6 is supported in the slots, its rear end may depend below the extension 5. The rear end is then lifted and the extension 5 projects down through the 60 aperture 7 therein. The pin 8 is next passed through the horizontal openings in the extension and lower yoke arm, which have been brought into register, and is held in place by a cotter, thus completing the as- 65 sembling of the device.

It will be seen that the pulling stresses are transmitted from the coupler butt to the yoke arms through the inwardly turned gibs 11, 11' and from the upper arm directly to 70 the vertical portion 3 and from the lower arm through the reduced extension to the said vertical portion.

In removing the lower arm the pin 8 is first withdrawn, which permits the rear end 75 of the arm to drop down below, and clear of, the extension 5, as is shown in dotted lines in Fig. 1. The member 6 may then be moved forwardly to disengage its forward end from the webs 4 and coupler butt.

The terms and expressions which I have employed are used as terms of description and not of limitation, and I have no intention, in the use of such terms and expressions, of excluding any mechanical equivalents of the features shown and described, or portions thereof, but recognize that various modifications are possible within the scope of the invention claimed.

What I claim is:

1. In a coupler yoke, an upper yoke arm having at its forward end a plurality of depending webs and at its rear end a depending vertical portion, a lower yoke arm having at its forward end an interlocking engagement with the webs and apertured at its rear end to take about the lower end of the vertical portion to provide a pulling engagement therewith.

2. In a coupler yoke, an upper yoke arm 100 having at its forward end a plurality of depending webs and at its rear end a depending vertical portion, the vertical portion having a reduced extension, a lower yoke arm having at its forward end a supporting 105 engagement with said webs and at its rear end being apertured to take about said reduced extension to provide a pulling engagement therewith.

3. In a coupler yoke, an upper yoke arm 110

having at its forward end a plurality of depending webs and at its rear end a depending vertical portion, the vertical portion having a reduced extension, and a lower yoke arm having at its rear end an interlocking pulling engagement with said reduced extension, the depending webs on the upper yoke arm carrying means for supporting the forward end of the lower yoke arm.

10 4. In a coupler yoke, an upper yoke arm

having at its rear end a depending vertical portion, a lower arm apertured to take about the lower end of the vertical portion to provide a pulling engagement therewith, each of said arms having a gib at its forward end 15 to engage a coupler butt, and means connecting the forward ends of said arms to hold said gibs in engagement with a coupler butt.

HUBERT L. SPENCE.
